UNITED STATES PATENT OFFICE

2,598,361

DRAINAGE VALVE

Max Dach, Flushing, N. Y.

Application August 21, 1945, Serial No. 611,859

1 Claim. (Cl. 137—103)

1
This invention relates to air tanks, and, more particularly, means for getting rid of excess moisture condensation and other matter.

It is well-known that water, dirt, oil and other foreign matter collect in the bottom of air and gas tanks and should be removed because, otherwise, it will be carried through the pipes to the devices that are operated by compressed gas, causing faulty operation and damage. This is particularly serious in cold weather when water or other condensation is apt to freeze in air lines and prevent operation of the brakes, doors and other devices.

An object of this invention is to provide means for automatically removing water or other condensation from tanks and to prevent the clogging of the lines.

Another object of the invention is to provide a device which will be simple in character, efficient in operation and which will require very little servicing.

Other objects and advantages of my invention will appear in the accompanying drawings in which—

Fig. 1 is a cross-sectional view of a form of my device shown attached to an air tank.

Fig. 2 is a modification of my device shown in cross-section.

Fig. 3 is a further modification.

Referring more particularly to the drawings, and particularly to Fig. 1 thereof, there is shown a conventional air tank 10 together with a cleaning device, shown by the numeral 11. This device consists essentially of two castings, 14 and 15, the casting 15 having an internally threaded flange 16 to receive the casting 14. Positioned between the castings is a diaphragm 17, upon which is positioned a spring 18 which bears against the top 19 of the cavity 20. Positioned in the casting 14 is a valve member 21, having an upper head 22 and a lower head 23 with a reduced portion 24. A valve member 21, and particularly the lower head 23 thereof, is a permanent magnet.

Running from the tank 10 to the casting 15 is a pipe 30 in which is situated the valve 31. The pipe 30 connects with the chamber 32 within the casting 15. Mounted in the chamber 32 is a screen 33 and a steel float 34. A passage 35 leads through the valve 36 to the atmosphere. Liquid will drain from the tank through the pipe 30 and the valve 31, which is normally open, into the chamber 32, causing the float 34 to rise.

The valve 21 is normally held in the upward position by the spring 26. When the float 34

2
rises to a predetermined height, the magnetized head 23 will move downwardly toward the float, thus bringing the reduced portion 24 into register with the passage 36, which is connected by means of a pipe 37 to the air tank 10. Air will pass through the passage 36 around the reduced portion of the valve through the passage 38 to the pipe 39, which leads to the piston 40, mounted in the cylinder 41. A spring 42 normally keeps the piston in the upward position, but the air will force the piston downwardly against the spring, rotating the arm 45, which, in turn, opens the valve 36 and rotates the arm 46 through the link 47 and the arm 48 to close the valve 31. This allows the water or other condensate to escape from the chamber 32 while at the same time preventing loss of air from the tank. As the air pressure and water are discharged from the chamber 32 the float 34 is left without support other than the pull of the magnetized head 23. This would be insufficient to hold the float against the pressure of the spring 18 bearing against the diaphragm 17 and the magnetic hold will be broken and the float 34 will drop. The spring 26 will move the valve upwardly so that the portion 50 will contact the seat 51 to prevent passage of air through the pipe 37 and will, at the same time, move the valve 52 away from the seat 53 to allow the air in the cylinder 41 to escape through the opening 55, thus the entire apparatus returns to its normal position.

In the modification shown in Figure 2, tank 10 is provided with a pipe 60 leading to a three-way valve 61. The valve 61 is operated by the piston 62 in the cylinder 63 and is normally held in the position shown by means of the spring 64 about the shaft 65 which operates the arm 66 of the valve 61. In the position shown the valve is so set that liquid from the tank may flow down the pipe 60 through the valve 61 and through the pipe 66 into the chamber 67 of the cleaner 70. When the level of the fluid in the chamber 67 rises the air will be forced through the passage 68 into the passage 71 under pressure and when the level of the fluid reaches a point where the magnet 71 is attracted to the steel float 72 through the diaphragm 73 and against the tension of the spring 74, the valve 75 will unseat and allow the air under pressure to pass through the passage 77 in the block 78 past the valve 75 through the passage 79 and the pipe 80 to the cylinder 63. Of course, when the valve 75 is then seated the valve 82 automatically closes. This will push the piston to the right, closing the passage 55 through the pipe 60 but opening the passage from

the pipe 66 to the drain 81, thus allowing the liquid in the chamber 67 to flow off. When the level of the liquid is dropped sufficiently the magnet will be released to reseat the valve 75 to cut off pressure from the tank to the cylinder 63. The spring 74 will return the piston to the left side of the cylinder and any excess air will be allowed to escape past the valve 82 through the drain 83.

It will be appreciated that the principle involved in both of the forms so far discussed is substantially identical except that different means of operating the discharge valves are disclosed.

In the form shown in Figure 3 the principle is substantially the same and the drainage from the tank 10 passes through the pipe 90 through the valve 91 into the chamber 93 through the screen 94 into the chamber 95. A float 96 with a magnet 97 operates on the member 98 through the diaphragm 99 against the spring 100. This closes the switch 101 which connects up the wires 102 and 103 to close the circuit operating the electro-magnetic switch 104. This allows the passage of air through the pipe 105 through the switch 104 through the pipe 106 to the piston 107 in the cylinder 108. The piston 107 has a shaft 109 engaging the arm 110 on the valve 91. As the piston moves to the left it opens the drain 111 to allow the escape of the excess fluid, and, at the same time, closes the passage from the pipe 90 into the valve 91. As the float drops, the spring 100 opens the switch 101 to de-energize the magnetic switch 104 and to return the parts to their original position.

It will be appreciated that other modifications of my invention may be made without departing from the spirit of the invention.

It will be appreciated that for the most efficient

operation of my device the control mechanism should be situated below the level of the tank so that liquid will normally flow downwardly through the drain into the operating mechanism.

5 I claim:

A device of the character described comprising a body having a chamber therein, a liquid inlet into said chamber, a valve on said inlet, a drainage outlet on said chamber and a valve for 10 said outlet, an air cylinder on said body and a piston in said cylinder, linkage between said piston and said drainage and inlet valves whereby one of said valves is opened as the other is closed, an air line for said piston and a magnetic valve positioned in said line normally closing it, said magnetic valve being positioned above said liquid chamber, a magnetic float in said chamber which when raised sufficiently by the level of liquid in the chamber will operate upon the magnetic valve to open the air line to the piston to cause said piston to open said drainage valve and to close the liquid inlet valve.

MAX DACH.
